ATTORNEY

UNITED STATES PATENT OFFICE.

ELI H. SLAYBAUGH, OF ALLIANCE, OHIO.

RAILWAY BLOCK-SIGNAL.

SPECIFICATION forming part of Letters Patent No. 329,092, dated October 27, 1885.

Application filed November 10, 1884. Serial No. 147,595. (No model.)

To all whom it may concern:

Be it known that I, ELI H. SLAYBAUGH, a citizen of the United States, residing at Alliance, in the county of Stark and State of Ohio, have invented certain new and useful Improvements in Railway Block-Signals; and I do hereby declare that the following is a full, clear, and exact description of the same, reference being had to the annexed drawings, making a part of this specification, and to the letters and figures of reference marked thereon, in which—

Figure 1 is an isometrical view. Fig. 2 is a detached view of slats and device for operating said slats.

The present invention has relation to railway-signals designed to signal a train at a telegraph-station and stop a train for orders or any other purpose; and its nature consists in the different parts and combination of parts, hereinafter described, and pointed out in the claims.

Similar letters of reference indicate corresponding parts in the drawings.

In the accompanying drawings, A represents the outside frame, which is substantially of the form shown in Fig. 1, the top of which is provided with the roof B, which may be of the form shown; or it may be of any other desired form. The roof B and the bottom C are attached to the frame A, as seen in the drawings.

The upper portion of the frame A is provided with the signal slats or strips D, which are substantially of the form shown in Fig. 1. As shown, five slats or strips are used; but any desired number may be used. These strips or slats are attached to the frame A at their upper and lower ends in such a manner that they will easily turn. These slats are painted different colors upon their opposite sides, such as a bright red upon one side and white upon the other. These slats or strips D are made of sheet iron or any other suitable material, and may be riveted or otherwise attached to the rods E, as seen in the drawings.

The top or upper ends of the rods E are provided with the cranks F, and these cranks are attached by the connecting-bar G, so that motion will be communicated to all of the slats D by the movement of one of these slats, said slats being so arranged that they will turn

half-way around without interfering with each other. The rod E, upon the center slat, D, is provided at its bottom or lower end with the beveled pinion H, which meshes in the segment I, as seen in Fig. 2.

Within the frame A is located the frame J, which is substantially of the form shown in the drawings, the sides of which are closed with sheet iron or other suitable material, one side being provided with a door, so that a lamp may be placed in said frame or removed. Two of the opposite sides of this frame J are provided with a lens, K, which are held in the frame J in any well-known manner. These lenses K are made of uncolored glass.

Upon the inside of the frame J are located the glasses L, which are substantially of the form shown, and are held in the desired position by the frame M. These glasses L are made of colored glass, the color of which should correspond with the color upon one side of the slats or strips D. The lower portion of the frame M is provided with the weight N, which is for the purpose of holding the glasses L in the position shown in Fig. 1, and also assisting in bringing said glasses in that position after they have been turned so as to show a white light.

The frame M is attached to the shaft O, as seen in Fig. 1, said shaft being attached to the support P, which is substantially of the form shown in the drawings, and is rigidly held in proper position by suitable clamping-bolts or rivets.

The upper portion of the frame M is provided with the lever or arm Q, which extends above the shaft O, as seen in Fig. 1, and is for the purpose of attaching the operating-rod R.

Only one of the glasses and connecting parts is shown in full, the other being broken away or sectioned, as appears in the drawings; but both are constructed and operate alike, although independent of each other.

In use the signal proper is placed at the required height upon a post, standard, or other frame-work, and the operating-rods R extend to the table of the operator. When the telegraph-office is located above the ground floor, and when the office is located upon the ground floor, the signal may be operated by means of cords.

It will be seen that by my peculiar arrange-

ment I am enabled to signal a train from either direction, and at the same time leave the signal in its normal condition upon one side, as each glass L operates independently of the other.

5 It will also be seen that on double-track roads I am enabled to signal a train coming from one direction and let a train pass coming from the opposite direction, if it is not desired to stop the train.

10 During the night a lamp or other light is placed in the frame or box J.

The operations of my invention are as follows: In case it is desired to signal a train, the colored glass is placed in the position shown 15 in Fig. 1 by movement of rod R, which movement at the same time turns the slats D, through the instrumentality of the rod O, the segment I, the pinion H, the cranks F, and the connecting-rod G.

20 The relative arrangement and relation of segment I, pinion H, and crank Q is such, as shown, that by moving rod R the slats D will make one-half a revolution while the glass L is making one-quarter of a revolution.

25 Having now fully described my invention, what I claim as new, and desire to secure by Letters Patent, is—

1. The combination of frame A, having on

opposite sides pivoted slats D, with frame J, within frame A, and containing on opposite 30 sides swinging glasses L, connected with said slats to move therewith, substantially as described.

2. In a signal, the combination of a series of pivoted slats, a swinging lens or glass connected to said slats to move with them, and a lever for moving said glass, substantially as described.

3. In a signal, the combination of a series of pivoted slats connected together and a pinion connected with one of said slats, a shaft having a segment engaging with said pinion, a glass connected to said shaft to move therewith, and a lever for turning said shaft, substantially as described.

4. The shaft O, provided with the segment I, in combination with the pinion H and the slats O, substantially as and for the purpose specified.

In testimony that I claim the above I have 50 hereunto subscribed my name in the presence of two witnesses.

ELI H. SLAYBAUGH.
